UNITED STATES PATENT OFFICE.

PETAR WAJDIĆ, OF STEELTON, PENNSYLVANIA.

MACHINE FOR SEWING LEATHER ARTICLES.

1,219,684.

Specification of Letters Patent. Patented Mar. 20, 1917.

Application filed July 31, 1914. Serial No. 854,421.

To all whom it may concern:

Be it known that I, PETAR WAJDIĆ, a subject of the King of Hungary, residing at Steelton, in the county of Dauphin and State of Pennsylvania, have invented certain new and useful Improvements in Machines for Sewing Leather Articles, of which the following is a specification, reference being had therein to the accompanying drawing.

This invention relates to a machine for sewing leather articles and has for its object to provide a machine having a needle operating and work feeding mechanism as hereinafter set forth, capable of being operated manually for sewing together a plurality of plies of leather.

Further objects of the invention are to provide a mechanism of such class which is simple in its construction and arrangement strong, durable, efficient and convenient in its use, readily set up and comparatively inexpensive to manufacture.

With the foregoing and other objects in view the invention consists of a novel construction, combination and arrangement of parts as hereinafter more specifically described and illustrated in the accompanying drawings, wherein is shown an embodiment 30 of the invention, but it is to be understood that changes, variations and modifications can be resorted to which come within the scope of the claims hereunto appended.

Although the machine is designed primarily for the sewing or stitching together of a plurality of plies of leather, yet it is to be understood that it can be employed for stitching or sewing together a plurality of any flexible material.

Figure 1 shows a side elevation of the machine having a portion thereof broken away as indicated in Fig. 2 by lines *a—a*.

Fig. 2 is a top plan view of the machine, and Fig. 3 is a detail perspective view 45 of the pivotal joint employed in the device.

Referring to the drawing in detail, 1 denotes the inner side of a bottom member. A similar member 40 lies parallel with the member 1 and the members terminate in an 50 integral handle 8. Near the front and rear of members 1 and 40 are braces 2 and 3 connecting them and formed integral with them. Between the handle 8 and brace 2 is a housing having side walls 4—4 connecting the members 1 and 40 and a top 6

made integral with the walls 4—4 and members 1 and 32. The top 5 has a hole centrally located therein. The forward ends of members 1 and 40 are connected by a plate 7, being perforated to allow the needle 60 to coöperate with the usual stitch forming mechanism 42.

The arms 2 and 3 and one side of the member 4 provide bearings for the longitudinally extending shaft 8 the latter having attached to its forward end a toothed wheel 9 which projects above the plate 7 and constitutes means for shifting material while being stitched, the teeth of said wheel 70 engaging beneath the goods to be operated upon whereby the goods may be fed forwardly when released by the sewing needle and held against the teeth by the operator but ratcheting thereover during the return movement of the wheel 9 when released by 75 the operator and unaffected the goods. The rear end of the shaft 8 is provided with a beveled gear 10.

Secured to the top edge of the member 1, are a pair of uprights 10 and 11, and pivotally connected to the upright 11, as at 12, is a longitudinally extending shank 13, of a vertically disposed needle holder 14, the latter having a needle 15 attached thereto and further provided with a thread guide 25 16, through which travels the thread 17, as it is unwound from the spool 18.

The shank 13 carries a post 19 for the spool 18 and the latter is maintained upon the post 19, by a shiftable retaining arm 20, 90 carried by a post 21 secured to the shank 13, rearwardly with respect to the post 19.

Pivotedly connected to the top of the upright 10, as at 21, is an operating lever 22, the latter having its forward end reduced and received between the sides of the forked rear end of the shank 13, the said sides being slotted as at 23 and the said lever 22 and shank 13 being pivotally connected as at 23, to the rear end of the shank, and its rearward end formed with a handle 24. The lever 22 has a lateral extension 25, formed with an opening 26, having the wall thereof provided with projections 27 and 28, which extend into a spiral groove 29, formed in a vertically disposed shaft 30. The shaft 30 extends up through the openings 5 and 26 and has its lower end provided with a beveled pinion 31 which meshes with the pinion 10.

Interposed between the lever 22 and member 1 is a spring 32 normally maintaining the lever 22 and member 1 in spaced relation and adapted to return the lever 22 and shank 13 to their normal positions in substantial alinement with each other after each actuation of the device.

The lever 22 is capable of being shifted upon its pivot 21, to cause the rotation of the shaft 30, such action will operate the shaft 8 by means of the shafts 30 and the gears 31 and 10. When the lower end of the lever 22 moves downward the rear end of the shank 13 will be carried upward, causing the lowering of the needle holders, the stitching of the material, and the feeding of the thread.

The spring 32 will not only actuate the lever 22 to starting position but will also restore the needle holder to such position.

What I claim is:—

1. A device of the class described comprising a base having a handle at its rear end and a needle plate at its forward end, spaced uprights upon the said base, a shank pivoted to the forward one of said uprights, a needle holder at the forward end of said shank adapted to operatively position a needle with respect to the said plate, a thread carrier upon the said shank, an operating lever pivoted to the rearward upright having loose pivotal connection with the adjacent end of the said shank and having a handle portion at its free end adjacent the said base handle, resilient return positioning means for said lever and shank positioned between said lever and base, the said lever and shank being normally in substan-

tial alinement with each other and in parallelism with the said base.

2. A device of the class described comprising a base having a handle at its rear end and a needle plate at its forward end, spaced uprights upon the said base, a shank pivoted to the forward one of said uprights, a needle holder at the forward end of said shank adapted to operatively position a needle with respect to the said plate, a thread carrier upon the said shank, an operating lever pivoted to the rearward upright having loose pivotal connection with the adjacent end of the said shank and having a handle portion at its free end adjacent the said base handle, resilient return positioning means for said lever and shank positioned between said lever and base, the said lever and shank being normally in substantial alinement with each other and in parallelism with the said base, laterally projecting arms and a housing carried by the said base, a shaft journaled through the said housing and arms, a work engaging feed wheel upon the forward end of said shaft projecting slightly above the receiving face of said plate, a pinion upon the opposite end of said shaft, a rotating member extending through said housing and lever and operatively connected to said pinion within the said housing, and rotation imparting connections between said rotating member and lever.

In testimony whereof I affix my signature in the presence of two witnesses.

PETAR WAJDIC.
